BY
Walton Harrison,
HIS ATTORNEY.

UNITED STATES PATENT OFFICE.

GEORGE W. CUMING, OF NEW YORK, N. Y., ASSIGNOR TO M. A. CUMING & CO., INC., OF NEW YORK, N. Y., A CORPORATION OF NEW YORK.

DIES FOR FORMING LEGGINGS.

Application filed March 2, 1923. Serial No. 622,427.

To all whom it may concern:

Be it known that I, GEORGE W. CUMING, a citizen of the United States, and resident of New York city, in the county of New York and State of New York, have invented 5 certain new and useful Improvements in Dies for Forming Leggings, of which the following is a full, clear, and concise description.

10 My invention relates to dies for forming leggings, and particularly leggings made of leather. It is a fact well known in this art, that in the manufacture of leather leggings the leather used as stock is seldom or never 15 uniform in thickness. If a number of blanks be cut out of pieces of leather which have been previously assorted as to size and thickness, it will be found that these blanks differ from each other greatly in thickness and that 20 even in the same individual blank, no matter how carefully selected, the leather will be substantially thicker in one portion than another.

Owing to the lack of uniformity in the 25 thickness of the leather and of the blanks made therefrom as just pointed out, there arises in the manufacture of leather leggings various difficulties. For instance if in a 30 particular blank the leather happens to be thin at one point and thicker at another, the finished legging made from this blank is apt to appear somewhat distorted, or to show a bump or a flat surface where none should 35 appear. These and other defects of the same general kind often cause the finished leggings to present an appearance suggestive 40 of inferiority and cheapness and thus militating against sale of the leggings, or at least tending to lower the prices at which they can be sold.

What I seek by my invention to do, therefore, is in forming the blanks into leggings, to give the outside of the blank a predetermined ideal shape, so that the inside of the 45 blank will carry all of the distortions, irregularities and defects due to differences in the thickness of the leather of the blank. By doing this, the various undesirable effects wrought by the differences in thickness of 50 different portions of the blank are effectively concealed, in that they are so located and arranged as to render them invisible to persons looking at the outer surfaces of the leggings, as worn in actual practice.

55 Following this idea, I employ two dies,

one known as the outer die and the other as the inner die, the outer die being provided with a metallic operating face of proper conformity to confer a predetermined ideal shape upon the outside of the legging blank, 60 the inner die being provided with a facing of thick rubber or other resilient material; and in connection with the inner die I use means for distending this rubber facing under pressure of a liquid or gaseous medium, 65 so as to firmly press the leather blank outwardly against the operating face of the outer die. By this arrangement, it follows that in the finished legging the outer surface thereof is substantially ideal in form, 70 this result being gained at the sacrifice of the form given to the inner surface of the legging.

By constructing and operating the dies as just indicated I accomplish another result 75 which is quite desirable, and that is, to cause the pressure applied to the blank to be distributed with substantial uniformity throughout the entire area of the blank.

In addition by my invention I seek, by 80 distributing the pressure applied to the blank, to prevent injury to the material used, and also to prevent the formation of wrinkles and creases in the blank, as the same is formed into the finished legging. 85

Reference is made to the accompanying drawing forming a part of this specification, and in which like reference characters indicate like parts throughout the several figures. 90

Figure 1 is a substantially vertical section through a pair of dies made in accordance with my invention.

Figure 2 is a side elevation of the mechanism shown in Figure 1. 95

Figure 3 is an end view, partly in section and partly in elevation, the mechanism shown in Figure 1.

A cap plate 4 is mounted upon posts 5, 100 four in number, and secured firmly thereto. For this purpose each post 5 is provided with a threaded end portion 6, which extends through an eye 7 with which the cap plate is provided, and nuts 8 and 9 are revolvably mounted upon the threaded portions 6 and 105 jammed against the eyes 7.

The outer die appears at 10 and engages a pair of cross beams 11. This carries a bolt 12 extending upwardly through a hole in the cap plate 4, and also through a beam 13 110

resting upon the cap plate. A nut 14 engages the upper end of the bolt 12. The die 10 carries a heat device, consisting in this instance of a gas pipe 15, held upon the die 10 by means of fastenings 16, and provided with burner holes 17. By means of the gas pipe thus provided with burner holes a number of gas flames 18 are caused to heat the die member, in the usual or any desired manner.

The die 10 is made entirely of metal, and is rather massive. Its general form may be defined roughly as saddle shaped, as may be understood from Figures 1 and 3. The operating face of the die appears at 17, and is given such form that when the leather blank is forced against it as elsewhere explained, the outer surface of such blank is given a predetermined ideal form.

20 A follower plate appears at 18 and is provided with four eyes 19, serving as bearings and encircling the posts 5, so that the follower plate is slideable relatively to these posts and to the cap plate 4, and thus movable relatively to the die 10.

Mounted upon the follower plate 18 are a pair of cross beams 20. Engaging the under side of the follower plate is another cross beam 21.

25 Detachably fitted upon the cross beams 20 is a shoe 22, provided with a pair of upturned edge portions 23, as shown more particularly in Figure 3. The shoe 22 carries a bolt 24 which extends downwardly through the cap plate 18, and the beam 21, and is detachably engaged by a nut 25. By unscrewing the nut 25 and thus disengaging it from the bolt 24, the shoe 22 may be raised directly upward, carrying the bolt 24 with it, the shoe and bolt being thus as a unit removable.

30 Mounted upon the shoe 22 is a core 26, made of metal and having a general contour mating that of the inner surface 10. The core 26 is hollow, and is provided with a 45 pair of flanges 27, integral with it and extending toward each other. The core 26 is further provided with a pair of end walls 28 and 29, integral with it.

35 A former appears at 30 and is essentially a pocket made of soft rubber and having a shape which externally is closely analogous to that of the core 26. The former 30 encloses and completely envelops the core 26, and is provided with a pair of oppositely disposed flange portions 31, extending toward each other. With the core 26 thus housed within the rubber former 30, the flange portions 27 of the core rest directly upon the rubber flange portions 31. The rubber former is further provided with heads 32 and 33 integral with it, as may be understood from Figure 1. Bolts 34 extend through holes in the shoe 22 and flanges 31 and 27, and are engaged by nuts 35. Engaging the heads 32 and 33 are end plates

22^a and 22^b, made of metal and conforming in shape to the heads 32, 33. Bolts 36 extend through the end plates 22^a, 22^b, heads 32, 33 and end plates 28 and 29. These bolts are engaged by nuts 37. The bolts 34 and 36 and the nuts 35 and 37 hold together the various parts with which they are immediately associated, as may be understood from Figure 1.

A leather blank to be formed into a legging is shown at 37, and is adapted to rest upon the rubber former 30. In the particular blank here shown the inner surface has irregularities, shown at 37^a. A pipe 38 extends upwardly through the shoe 22 and core 26. This pipe is provided with a hand valve 39, and with a portion 38^a having sufficient flexibility to allow for vertical movement of the follower plate 18, and the lower die, which is carried thereby.

25 The follower plate 18 carries an extending member 40, and pivoted to this is a link 41. A flexible connection 42, which may be a cable or a rope, is connected with the link 41 and with a rocking pulley 43, this rocking pulley being journaled upon the cap plate 4, and thus supported by the framework. A flexible connection 44, such as a rope or cable, is connected with the rocking pulley 43 and is used for actuating the same.

30 This rocking pulley 43 and parts immediately associated therewith are employed in connection with the raising and lowering of the follower plate 18, and are thus used in actuating the lower die. Since, however, the raising and lowering of one die member relatively to the other is a feature old in the art, the particular mechanism used for this purpose is not essential to my invention.

35 The upper die being heated, for instance by gas as above described and as here shown, and a blank 37 being properly moistened and laid upon the lower die so as to engage the former 30, the follower plate 18 is raised, and then compressed air or other fluid, supplied through the pipes 38^a and 38, is admitted between the core 26 and the former 30. This distends the former 30, so as to force it outwardly. The rubber former, thus distended, by its pressure against the blank 37 forces this blank tightly against the operating face of the upper die, so as to give shape to the leather blank.

40 The net result is that the finished legging is in outer appearances substantially perfect as to form, any unevenness due to differences in thickness of the stock material at different points being taken care of by the contour conferred upon the inner surface 120 of the legging. Therefore if a particular portion of the leather blank happens to be 125 thick as compared with another portion thereof, the differences in thickness are not apparent to the eye of the observer if he 130

looks, as he usually does, only at the outside of the finished legging.

The operation of my device is as follows:

The lower die being operated as above described, and the leather blanks used as stock being rested in position, pressed as above described, and removed by hand one at a time, the leather blanks are converted into finished leggings, any holes required for use 10 in connection with fastenings being made in any appropriate manner.

Having thus described my invention, what I claim as new and desire to secure by Letters Patent is as follows:

15 1. A device of the character described, comprising an outer die provided with an operating face of proper configuration to form the outer surface of a legging, and an inner die movable relatively to said outer die, and comprising a hollow core and a rubber former fitted upon said hollow core, said core and said former having such configuration that the outer surface of said former 20 mates the operating face of said first mentioned die, and means for supplying a medium under pressure between said core and said rubber former, for the purpose of distending said rubber former.

2. A device of the character described, 25 comprising an outer die and an inner die movable relatively to said outer die, said outer die having an operating face conforming substantially to the ideal shape required for the outer surface of a legging, said inner die comprising a core and a rubber former carried by said core, said core and said rubber former each having a conformity substantially mating the conformity of the operating face of said upper die, and a 30 pipe extending through said core and into proximity to said rubber former carried thereby, for the purpose of discharging in between said core and said rubber former a medium under pressure in order to distend 35 said rubber former.

3. A device of the character described, 40 comprising an outer die member provided with an operating face of suitable shape to form the outer surface of a legging, an inner die provided with an outer face of proper conformity to form the inner surface of said legging, said inner die being further provided with a rubber former, and means for forcing in between said inner die and 45 said rubber former a medium under pressure, for the purpose of distending said rubber former.

4. The combination of a fixed die, a

framework supporting the same, a follower plate mounted upon said framework and 50 movable relatively to said framework and to said fixed die, a second die mounted upon said follower plate and movable therewith, said second mentioned die comprising a shoe provided with flange portions, a rubber former carried by said shoe and engaging 55 said flange portions, said rubber former being provided with a pair of oppositely disposed flange portions extending toward each other, and a hollow core enclosed within 60 said rubber former and provided with a pair of oppositely disposed flange portions 65 extending toward each other and resting upon said pair of flange portions of said rubber former, bolts extending through said 70 shoe and through said flange portions of said rubber former and said flange portions of said core, and means for forcing between said core and said rubber former a medium 75 under pressure, for the purpose of distending said rubber former.

5. A device of the character described comprising a frame, a die supported thereupon, a follower plate supported by said frame and movable relatively to said die, 80 a shoe carried by said follower plate, a rubber former provided with a pair of oppositely disposed flange portions engaging said shoe and extending toward each other, said rubber former being hollow, a hollow core 85 enclosed within said rubber former and provided with flanges, fastening members engaging said shoe and also engaging the flanges of said rubber former and the flanges of said hollow core for the purpose 90 of holding said shoe and said core together, and means for forcing in between said hollow core and said rubber former a medium 95 under pressure, for the purpose of distending said hollow former.

100 6. A device of the character described comprising an outer die member provided with an operating face of suitable shape to form the outer surface of a legging, a follower plate movable relatively to said die, 105 a shoe carried by said follower plate, a hollow core and a hollow rubber former carried by said shoe said hollow former enclosing said hollow core, said hollow former and said hollow core having together a conformity 110 suitable for forming the inner surface of a legging.

Signed at New York city, in the county of New York and State of New York, this 28th day of February, 1923.

GEORGE W. CUMING.
